UNITED STATES PATENT OFFICE

FREDERICK W. MARTIN, OF BROOKLYN, NEW YORK, ASSIGNOR TO FRANKLIN RAILWAY SUPPLY COMPANY, A CORPORATION OF DELAWARE

DRIVING-BOX LUBRICATOR

Application filed November 17, 1923. Serial No. 675,248.

This invention relates to driving box lubricators.

Heretofore in this art, the cellar which contains the grease cake or other lubricant has been provided with lugs through which the cellar bolts for securing the cellar to the driving box are passed. In this arrangement it is necessary to remove a cellar bolt in order to take off the end plates for the purpose of 10 repacking the cellar. This operation is sometimes rather difficult and in addition when the cellar bolt is taken off, the end plate is separated from the cellar and very often lost. This is practically standard equipment at 15 the present time.

Attempts have also been made to fasten the end plate from the driving box itself, but such arrangements have not been found practical and are open to the same objections 20 above set forth, namely, certain parts must be detached (and may be lost) in order to permit of the removal of the end plate.

One of the primary objects of my invention is to provide a construction in which 25 the foregoing difficulties are obviated.

More specifically it is an object of my invention to provide a self-contained driving box cellar and end plate therefor, so constructed and arranged that the lubricator 30 cavity of the cellar may be exposed without detaching the end plate.

Another object is the provision of an arrangement by virtue of which no parts need to be removed in order to move the end plate 35 to expose the cavity of the cellar.

Still another object is to provide what may be termed a "snap" end plate for driving box lubricating cellars.

The foregoing together with such other 40 objects as may hereinafter appear, or are incident to my invention, are obtained by means of a construction which I have illustrated in preferred form in the accompanying drawing wherein:

Fig. 1 is a fragmentary side elevation of a driving box illustrating the application of my improved lubricating device;

Fig. 2 is a section taken on the line 2—2 50 of Fig. 1;

Fig. 3 is a fragmentary sectional view illustrating certain details of my invention.

Referring now to the drawing the reference character "A" indicates a typical driving box having a bearing brass 7 for the axle 8, and the cellar is indicated as a whole by the reference character "B". In general, the cellar is of customary construction and is provided with the usual arcuate perforated plate 9, the follower plate 10, the spring 11 55 for pressing the follower plate 10 with its grease cake toward the perforated plate 9, and the depending eye rods 12 for pulling down the follower plate 10 when inserting a new grease cake.

At each end of each side of the cellar there is a downwardly projecting lug 13 through which the cellar bolts 14 60 for connecting the cellar to the driving box pass. The open end of the cellar is closed by the end plate 14 65 which is loosely but directly carried by the cellar for swinging movement outward, uncovering the lubricator cavity of the cellar. For this purpose the end plate is provided with a downwardly extending clevis-like lug 70 75 15 and the cellar is provided with a pair of spaced lugs 16 which carry a pin 17 passing through the slots 18 in the arms of the clevis lug 15. The ends of the pin may be riveted over as shown.

The end plate is held in closed position as follows: at each side, the open end of the cellar is provided with the lug 19, the top surface of which is notched or grooved as at 20 so that the lug may be said to be somewhat hook-like; and at a lower level the cellar is provided with the similarly shaped lugs 21 which extend upwardly and outwardly from the lugs or ears 13 at such end of the cellar. The lugs 19 and 21 are offset vertically and the end plate is of such shape that it is seated in the lugs as indicated in Fig. 1 when in closed position. Sufficient clearance is provided between the end plate and the axle to permit of the end plate being raised sufficiently to clear the hooks of the lugs, when it may be swung outwardly. This upward movement is made possible by virtue of the slots 18 before mentioned.

Gravity may hold the end plate in position 100

in the spaced seats provided by the pairs of lugs 19 and 21, but I prefer to provide means whereby the end plate is snapped into position and yieldingly held. For this purpose I provide the spring 22, one end of which passes over the pin 23 carried by the end plate and the other end of which passes over the pin 17. The tension of the spring holds the end plate in position.

10 To release the end plate from engagement with the lugs 19 and 21, a tool is inserted into either of the spaces 24 formed between the bottom of the end plate and the lugs 16, and the end plate is pried upwardly a sufficient 15 distance to clear the hooks of the lugs. When closing the end plate, it rides over the rounded surfaces 25 of the lugs 19 and 21 against the tension of the spring, and snaps into place.

It will be seen from the foregoing that irrespective of whether or not the spring is employed, the end plate and the cellar constitute a self-contained structure and that the end plate may be moved to uncover the lubricator cavity without undoing or detaching 25 any parts whatsoever. If the locomotive should be lifted with the wheels in place and should the axle bear on the end plate, no breakage of the cellar will occur as the pairs of lugs 19 and 21 are in line with the end 30 plate and take the thrust substantially vertically downward. The other advantages will be readily understood by those skilled in the art.

I claim:

35 1. A self-contained driving box lubricating cellar and an end plate directly carried on the cellar for movement uncovering the lubricator cavity of the cellar, together with snap means including hook seat means for releasably holding the plate in closed position.

2. In combination, a driving box lubricating cellar, an end plate loosely carried on the cellar, and snap means including hook seat means holding the plate in closed position.

45 3. In combination, a driving box lubricating cellar, having hook seat means, an end plate, and automatic snap means yieldingly holding the plate in closed position in engagement with the hook seat means.

50 4. In combination, a driving box lubricating cellar having hook-like end plate holding means, and an end plate engaged thereby, together with yielding means for holding said plate in engagement with said holding means, the cellar and plate being self-contained.

55 5. In combination, a driving box lubricating cellar having a pair of eyes on each side at each end thereof for attachment to an adjacent part, and an end plate for one end of the cellar, the eyes at said end having seat lugs in line with the end plate and adapted to support the plate when in closed position.

60 6. In combination, a driving box lubricating cellar and a snap end plate cover there-

for, said cellar and plate being constructed to provide opposing surfaces spaced apart to permit insertion of a prying tool.

7. In combination, a driving box lubricating cellar having cover plate engaging means thereon and a snap cover plate pivoted thereto but displaceable transversely of the pivot axis, said plate engaging said means when in closed position and being adapted to be opened on displacement.

75 8. In combination, a driving box lubricating cellar having cover plate engaging means thereon and a snap cover plate therefor displaceably secured thereto, said plate engaging said means when in closed position and being adapted to be opened on displacement, and said cellar and plate being constructed to provide opposing surfaces spaced apart to permit insertion of a displacing tool.

80 85 In testimony whereof I have hereunto signed my name.

FREDERICK W. MARTIN.
